UNITED STATES PATENT OFFICE

HARRISON B. WALTER, OF CHICAGO, ILLINOIS, ASSIGNOR TO CONTAINER CORPORATION OF AMERICA, OF CHICAGO, ILLINOIS, A CORPORATION OF DELAWARE

CONTAINER

Application filed May 23, 1930. Serial No. 454,965.

The invention relates to shipping containers, and more particularly to that type of shipping container which, after being received by the retailer, may be readily adapted for display and dispensing purposes, one object of the invention being to provide a relatively strong, sturdy and inexpensive container of this type which is simple in construction and capable of being readily assembled, packed and sealed by the packer, and at the same time permitting it to be easily opened and arranged for display and dispensing purposes. A further object of the invention is to provide a container which, when opened for unpacking, will be adapted for ready and effective assembly with dispensing and display covers of more or less usual form.

The present application involves certain features in common with the copending application of Harrison B. Walter, Serial No. 401,068, filed October 21, 1929.

The invention may be more readily understood by reference to the accompanying drawings, and the more detailed description thereof which follows, and which are intended as illustrative only.

In the drawings,

Fig. 1 is a perspective view of a portion of a container embodying the invention, the container having a closure or cover assembled thereon;

Fig. 2 is a plan view of a blank from which the container is formed;

Fig. 3 is a plan view of the blank forming the closure member for the container; and

Fig. 4 is a perspective view showing both the container and cover, these parts being separated to more clearly illustrate the details of each.

The present embodiment of the invention provides a container which is especially adapted for canned goods. The box is of sturdy construction and is of such form that a number of the boxes may be stacked before sealing. After shipping, the box can be opened up for inspection of the contents and closed for temporary handling purposes by merely replacing the cover member over the flaps of the box.

Referring more particularly to the draw-

ings, Fig. 2 illustrates a blank from which the body of the container is formed. The blank indicated as a whole by the reference numeral 35 is suitably scored and slotted to provide a bottom portion 36, side walls 37-37 and flaps 37'-37' formed at the outer edges of the side wall portions. The bottom and side wall portions have respective end extensions 36a, 37a and 37a. The numeral 38 indicates transverse score lines and the numeral 39 indicates longitudinal score lines. Slots 40 are formed in the blank to separate the end extensions.

The end extensions 37a-37a are of the same width as the side wall portions 37, and of a length equal to approximately one-half the width of the bottom portion 36, to provide an end closure for the container, as clearly illustrated in Fig. 4. In the present instance, the end extensions 37a-37a are shown as of such length as to somewhat overlap each other when the container has been set up. The extensions 36a are shorter than the depth of the container, so that when folded against and attached to the extensions 37a-37a by rivets 41, the upper edges of extensions 36a will be located below the top of the container. As shown, the rivets 41 are placed near the side and top edges of the extensions 36a to provide pockets or spaces 42 opening at the top of the extensions 36a between the rivets 41.

The closure for this form of container comprises a blank 43 shown in Fig. 3, having a top portion 44 and reduced or tapering end flaps 45 connected to the top portion by score lines 46.

The length of the flap extensions 36a is in general immaterial, it being only necessary that the extensions be secured to the end flaps 37a-37a so that there will be formed a pocket for the flaps 45 opening anywhere from a point adjacent the upper edges of the flaps 37a-37a to a point lower down, but high enough so that the ends of the flaps 45 will be engaged within the pocket.

The flaps 37'-37' are preferably of such length as to extend to the center line 50 of the box when folded over as indicated in Fig. 1. The score lines 39 at the juncture of the

sides 37 and flaps 37' are preferably impressed in the material of the blank in such manner as to provide a rib 15 extending slightly above the top of the flap 37' and a second rib

- 5 16 extending laterally slightly beyond the side 37. Intermediate the ribs 15 and 16 there is a substantially flat inclined surface 17, the purpose of which is to facilitate the application of a display cover in the manner described in my copending application Serial No. 401,068 filed October 21, 1929.

The method of assembling the cover 44 upon the container is best understood by reference to Fig. 4. The flaps 45 are inserted 15 in the pockets 42 formed between the end extensions 36a and the flaps 37a-37a. These flaps may or may not, as desired, be coated with adhesive before their insertion into the pockets. The flaps 37'-37' are then folded 20 over the closure 44, meeting along the line 50 (see Fig. 1) and a strip of adhesive paper 51 is applied over the closure line 50 and extends downwardly over the flaps 45 of the closure member and partway down the end extensions 36a.

After the box is packed and has been sealed as just described, it may be opened by slitting the gummed tape 51 along the center line 50, whereupon the flaps 37'-37' may be 30 folded back and the closure member 44 may be lifted off to be replaced if desired by the dispensing and display cover. In case the flaps 45 have been secured in place by adhesive, these flaps are allowed to remain in place 35 and the top portion 44 of the cover member is removed by severing it from the flaps 45 along lines adjacent the score lines 46 at the ends of the top portion. It is generally intended, however, that the cover 44 should be applied 40 without the use of adhesive on the flaps 45 and accordingly the closure member may be lifted off at will and replaced when it is desired to again cover the box. When this is 45 done, the flaps 37'-37' are generally folded down first, and the cover 44 with its flaps 45 extending into the pockets is applied over the top of the flaps 37'-37'.

Where a special display cover is to be employed in place of the cover 44, the flaps 50 37'-37' are preferably cut off adjacent the score lines 39-39 so as to expose the contents of the box to view.

It is obvious that many of the details of 55 the invention may be modified without departing from the broad principles involved. For example, the flaps 36a might be divided into two parts, meeting along a central vertical line and rivets might be applied adjacent this line as well as along the outer edges. 60 This would result in the formation of two pockets on each end of the box, and in such case the closure member might be provided with similarly divided flaps, one portion being adapted to go in one pocket and the other 65 in the other pocket.

What I claim is:

A shipping container comprising a blank of fiber or paper board providing a bottom and two side walls, flaps at each end of the bottom and the two side walls, means for securing said side and bottom wall flaps together to provide a pocket in each end of the box, a removable and separate cover likewise formed of fiber or paper board, said cover comprising a top and beveled end flaps, 70 said flaps fitting within said pockets, and the top providing a closure for said container, said side walls having additional flaps formed integral therewith extending inwardly from the top edges of the sides, where- 75 by said last-mentioned flaps cooperate with said removable and separate cover to form a cover of a plurality of thicknesses for said container.

Signed at Chicago, Illinois this 20th day 80 of May, 1930.

HARRISON B. WALTER.
